(57) **CLAIM**

The ornamental design for docking station, as shown and described.

DESCRIPTION

FIG. 1 is a front perspective view of the docking station showing our new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and

FIG. 8 is a left side elevation view thereof.

FIG. 9 is a front perspective view of a second embodiment of the docking station showing our new design with fabric covered regions that are represented with a cross-hatched pattern;

FIG. 10 is a rear perspective view thereof;

FIG. 11 is a front elevation view thereof;

FIG. 12 is a rear elevation view thereof;

FIG. 13 is a top plan view thereof;

FIG. 14 is a bottom plan view thereof;

FIG. 15 is a right side elevation view thereof; and,

FIG. 16 is a left side elevation view thereof.

The broken lines shown in the figures form no part of the claimed design.
